UNITED STATES PATENT OFFICE.

FRANK H. COON, OF MINNEAPOLIS, MINNESOTA.

CLUTCH-LOCK FOR AUTOMOBILES.

1,097,081.

Specification of Letters Patent.

Patented May 19, 1914.

Application filed December 19, 1913. Serial No. 807,633.

To all whom it may concern:

Be it known that I, FRANK H. COON, a citizen of the United States, residing at Minneapolis, in the county of Hennepin and 5 State of Minnesota, have invented certain new and useful Improvements in Clutch-Locks for Automobiles; and I do hereby declare the following to be a full, clear, and exact description of the invention, such as 10 will enable others skilled in the art to which it appertains to make and use the same.

My invention has for its object to provide an extremely simple and highly efficient clutch lock for automobiles, and to 15 such ends, generally stated, the invention consists of the novel devices and combinations of devices hereinafter described and defined in the claims.

It is a well known fact that the clutch of 20 an automobile is kept in operation by the pressure of a foot of the chauffeur on the clutch lever and when the foot is removed, the clutch lever is automatically moved to throw the clutch out of action. Hitherto, a 25 demountable or detachable casing has been wrapped around the stem of the clutch lever between the foot piece thereof, and the toe board, but such a device is subject to the 30 objection that it is liable to become lost, or misplaced, and hence, not available for use when wanted.

My invention provides a lock lever which is pivoted to the toe board adjacent to the 35 stem of the clutch lever and is adapted to be turned to and from an operative position, to rest upon the toe board when out of use, and to be turned under the foot piece of the clutch lever and locked to the said lever, when it is desired to lock the clutch lever 40 with the clutch in an inoperative or open position.

In the accompanying drawings which illustrate the invention, like characters indicate like parts throughout the several views.

Referring to the drawings, Figure 1 is a 45 view partly in side elevation and partly in section illustrating my invention applied in operative position; Fig. 2 is a side elevation of the lever locking device removed from 50 working position; Fig. 3 is a plan elevation of the same; and Fig. 4 is an elevation looking at the free end of the lock lever with the lock proper removed.

The numeral 1 indicates the heel board 55 and the numeral 2 the toe board of an automobile, the said toe board having the cus-

tomary passage 3 for the stem of the clutch lever 4. This clutch lever 4 is provided with the customary foot piece 5 at the upper end of its stem.

The lock lever 6 is preferably channel-shaped in cross section, being advisably formed from sheet steel, and at its lower end pivotally connected by a strong double headed rivet 7 to the upper end of a metallic anchoring bracket 8. This anchoring bracket 8, as shown, is formed with a rectangular body portion that is extended through the upper portion of the passage 3 and is rigidly secured by bolts, nuts, screws, or other suitable devices to the toe board 2. This lock lever 6 is of such length that when the clutch lever is in its normal or inoperative position, and the said lock lever is then turned into an operative 75 position shown by full lines in Fig. 1, its free end will straddle the upper end of the clutch lever stem in such close engagement with the foot piece 5 that the said lever cannot be forced into a position to render the 80 clutch operative. To secure the lock lever 6 in such operative position, it is shown as provided with a rigidly secured metallic yoke 9, preferably constructed of hardened steel and having laterally bent ends, to one 85 of which ends, a pad lock 10 is pivoted at 11. The other laterally bent prong of the said yoke 9 is made hook-shaped or is provided with a lock notch 12, and the case of 90 the pad lock 10, at one side, is provided with an opening adapted to receive the said notched end of the yoke. The pad lock may be of any suitable type having a detent for engagement with the notched end 12 of the yoke 9. Preferably, the said lock 10 is of 95 the general type known to the trade either as a Yale or Eagle lock, which type of locks have keys of such different character that there are practically no duplicate keys.

The lock 10 is of such form that when it 100 is turned into the position indicated by dotted lines in Fig. 3, the lock lever 6 may be freely moved to and from an operative position. When the said lock is turned into the position shown by full lines in Fig. 3, 105 and is interlocked to the notched end 12 of the yoke 9, it forms a bridge across the ends of the yoke which securely holds the said lock lever interlocked to the stem of the clutch lever.

Obviously, a clutch lever lock of the kind described cannot be displaced or lost and is

always available for use when wanted. Its efficiency is obvious.

In the specification, the parts 1 and 2 have been respectively designated as heel board 5 and toe board, because those are terms under which they are generally known, but as a broad term, they may be designated as a foot board or rest.

What I claim is:

- 10 1. The combination with a foot board and clutch operating lever of an automobile, said lever having a stem portion extended through said foot board and provided with a foot piece, of a lock lever pivoted to said 15 foot board in the vicinity of the stem of said lever arranged to be turned under into an operative position approximately parallel to the stem of said clutch lever and with its free end under the foot piece of said lever, 20 and a key operated lock applicable to the free end of said lock lever, to thereby lock said clutch lever.
2. The combination with a foot board and clutch operating lever of an automobile, said 25 lever having a stem portion extended through said foot board, and provided with a foot piece, of a lock lever pivoted to said foot board in the vicinity of said lever and adapted to be turned with its free end under 30 said foot piece into a position to hold said

clutch lever in an inoperative position, said lock lever having a channel-shaped upper end adapted to embrace the stem of said clutch lever, and a key-operated lock applicable to the channel-shaped free end of said lever to secure the same in an operative position interlocked with the stem of said clutch lever.

3. The combination with a foot board and clutch operating lever of an automobile, said 40 lever having a stem portion extended through said foot board, and provided with a foot piece, of a lock lever pivoted to said foot board in the vicinity of said lever and adapted to be turned with its free end under 45 said foot piece into a position to hold said clutch lever in an inoperative position, a yoke applied to the free end of said lock lever and adapted to straddle the stem of said clutch lever, and a key-operated lock 50 pivoted to one of the prongs of said yoke and adapted to be interlocked with the other prong thereof, substantially as described.

In testimony whereof I affix my signature in presence of two witnesses.

FRANK H. COON.
